UNITED STATES PATENT OFFICE.

HENRY L. HASKELL, OF LUDINGTON, MICHIGAN, ASSIGNOR TO HASKELITE MANUFACTURING CORPORATION, OF GRAND RAPIDS, MICHIGAN, A CORPORATION OF MICHIGAN.

PADDLE AND OAR.

1,263,411.

Specification of Letters Patent. Patented Apr. 23, 1918.

Application filed November 27, 1916. Serial No. 133,624.

To all whom it may concern:

Be it known that I, HENRY L. HASKELL, a citizen of the United States, residing at Ludington, Michigan, have invented certain new and useful Improvements in Paddles and Oars, of which the following is a specification.

This invention relates to improvements in paddles and oars.

10 In the manufacture of paddles and oars, it is particularly desirable that they shall be light and at the same time very strong. For that reason, in the manufacture of paddles and oars of the better grade, it has been common practice to select wood of light weight and straight grain, such as spruce, and only clear stock can be successfully used, and even with this care in selecting stock for the manufacture the blades frequently 15 split and are likely to become cracked and warped when subjected to the water and sun.

The main objects of my invention are:

First, to provide an improved paddle or oar which is light in weight and strong and durable and not likely to crack or warp.

Second, to provide an improved paddle or oar which is very economical to produce and can be made of stock not adapted for use in the manufacture of paddles and oars as 20 now commonly manufactured.

Further objects, and objects relating to structural details, will definitely appear from the detailed description to follow.

I accomplish the objects of my invention 35 by the devices and means described in the following specification. The invention is clearly defined and pointed out in the claims.

A structure which is a preferred embodiment of my invention is clearly illustrated 40 in the accompanying drawing forming a part of this specification, in which:

Figure I is a side view of a canoe paddle embodying the features of my invention.

Fig. II is a perspective view of the intermediate veneer section.

Fig. III is a cross section through the blade on a line corresponding to line 3—3 of Fig. I.

Fig. IV is a cross section through the handle on a line corresponding to line 4—4 of Fig. I.

Fig. V is a detail longitudinal section of the handle on a line corresponding to line 5—5 of Fig. I.

Fig. VI is a detail longitudinal section

of a modified form of my invention in which the blade is provided with a longitudinal kerf adapted to receive the intermediate veneer section.

Fig. VII is a detail longitudinal section 60 corresponding to that of Fig. VI with the intermediate veneer section inserted.

Fig. VIII is a detail longitudinal section 65 of a modified form of my invention in which the blade is longitudinally curved.

Fig. IX is a detail view partially in longitudinal section of a "spoon" paddle or oar embodying the features of my invention.

Fig. X is a transverse section on a line 70 corresponding to line 10—10 of Fig. IX.

Fig. XI is a detail longitudinal section 75 of another modified form of my invention in which the blade is formed separately of veneer and attached to the handle.

In the drawing, similar reference characters refer to similar parts throughout the several views, and the sectional views are taken looking in the direction of the little arrows at the ends of the section lines. 80

Referring to the drawing, 1 designates the handle portion, 2 the blade portion of the oar or paddle illustrated in Figs. I to V inclusive.

The paddle is built up of outer sections 3 85 having integral handle and blade portions and an intermediate section 4 also having integral blade and handle portions. The outer sections are formed of wood with the grain of the wood running lengthwise. 90 These outer sections are preferably formed of spruce which is a wood usually having a straight grain and is comparatively light in weight. The inner section 4 is formed of a thin veneer of hard wood preferably 95 maple and is disposed between the outer sections with its grain running crosswise thereof.

The inner faces of the outer section and the intermediate section are secured together throughout by a waterproof glue or cement. The inner section extends from edge to edge and from end to end of the outer sections. 100

By thus arranging the sections the paddles or oars may be made light and at the same time are so reinforced that they are not easily broken and do not warp or crack when subjected to water and sun.

In manufacturing it is preferred practice 110

to glue or cement the sections together and then shape the paddle in the same manner as though it were formed of a single piece.

By building up the stock in this way 5 relatively thin stock may be used for the side sections and it is well understood that such stock is more economical than the thicker stock, and, further, the paddles or oars are very much stronger and more 10 durable than when formed of solid stock.

In the modification shown in Figs. VI and VII, the handle portion 5 and the blade portions 6 are formed of a single piece of stock, the blade having a longitudinal kerf 15 7 therein into which the veneer section 8 is inserted, thereby greatly strengthening and reinforcing the blade. In this embodiment the oars or paddles are formed with the grain running lengthwise, while the 20 veneer insert 8 is disposed with its grain running cross wise so that it reinforces the blade permitting it to be made very thin and light and at the same time it is very strong and durable. The reinforcing 25 section 8 is coated with glue before inserting in the kerf and after it is inserted, the outer portions 6 of the blade are clamped upon it until the parts are united throughout.

In the modification shown in Fig. VIII, 30 the end of the blade is curved longitudinally. Owing to the reinforcing and supporting of the blade by means of the veneer insert, a strong and durable curved blade is provided. In the manufacture of such blades as shown 35 in Fig. VIII, the sections are secured together and then shaped by steaming and pressing.

The modifications shown in Figs. IX and X are substantially those shown in Figs. 40 VI and VII except that the blade 9 is a "spoon" blade, the structure particularly lending itself to the forming of such blades.

The "spoon" blade is formed in the same manner as the curved blade.

45 In the modification shown in Fig. XI, the blade 10 is built up of veneer and inserted into the handle 11 into which it is

secured by means of the rivets 12. The blade here shown is also a "spoon" blade.

The paddles and oar embodying my improvements are very strong and durable and at the same time are light in weight and economical to produce. I have not attempted to illustrate or describe all the embodiments of my improvements which I 55 contemplate as I believe the disclosure made will enable those skilled in the art to which my improvements relate to embody or adapt the same as may be desired.

Having thus described my invention what 60 I claim as new and desire to secure by Letters Patent, is:

1. As an article of manufacture, a paddle or oar comprising a pair of outer longitudinal sections formed with the grain of the 65 wood running lengthwise and consisting of integral blade and handle portions, and an intermediate section of hard wood veneer formed with the grain of the wood running crosswise and consisting of integral blades 70 and handle portions disposed between the outer sections and extending from end to end and from edge to edge thereof and secured thereto throughout by waterproof cement. 75

2. As an article of manufacture, a paddle or oar comprising outer longitudinal sections formed of wood with the grain of the wood running lengthwise and consisting of integral blade and paddle portions, and an intermediate section of wood veneer formed with the grain of the wood running crosswise disposed between the outer sections and extending from edge to edge of the blade thereof and secured throughout by waterproof cement. 85

In witness whereof I have hereunto set my hand and seal in the presence of two witnesses.

HENRY L. HASKELL. [L. S.]
